(57) **CLAIM**

The ornamental design for a dental apparatus having unilateral bite block, as shown and described.

DESCRIPTION

FIG. 1 is a perspective view of a maxillary appliance of a dental apparatus having unilateral bite block in accordance with the present design, shown with a mandibular appliance (of FIG. 2) removed for ease of illustration;

FIG. 2 is a perspective view of a mandibular appliance of a dental apparatus having unilateral bite block in accordance with the present design, shown with a maxillary appliance removed for ease of illustration;

FIG. 3 is a right, side view of the dental apparatus having unilateral bite block illustrating the maxillary appliance positioned superior to the mandibular appliance;

FIG. 4 is a left, side view of the dental apparatus having unilateral bite block of FIG. 3;

FIG. 5 is a front view of the dental apparatus having unilateral bite block of FIGS. 3 and 4;

FIG. 6 is a bottom view of the maxillary appliance of FIG. 1;

FIG. 7 is a top view of the maxillary appliance of FIGS. 1 and 6;

FIG. 8 is a top view of the mandibular appliance of FIG. 2; FIG. 9 is a bottom view of the mandibular appliance of FIGS. 2 and 8;

FIG. 10 is a perspective view of the dental apparatus having unilateral bite block of FIGS. 3 to 5 positioned on a user's teeth; and,

FIG. 11 is a perspective view of the dental apparatus having unilateral bite block positioned on a user's teeth with the bite blocks of the maxillary appliance and the mandibular appliance illustrated on a left side of each of the maxillary appliance and the mandibular appliance.

The broken lines provided in the drawings form no part of the claimed design.

1 Claim, 6 Drawing Sheets
